C. D. BONSALL

CARLINE

Filed Feb. 23. 1922

Inventor:
Charles D. Tousall,
by Daniel C. Clegg,
his attorney.

UNITED STATES PATENT OFFICE.

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA.

CARLINE.

Application filed February 23, 1922. Serial No. 538,652.

To all whom it may concern:

Be it known that I, CHARLES DAVID BONSALL, a citizen of the United States, and a resident of the city of Pittsburgh, in the county of Allegheny and State of Pennsylvania, have invented a certain new and useful Improvement in Carlines, of which the following is a specification.

My invention relates to carlines and has for its principal objects to devise a carline that is adapted to be made from a single sheet of metal; to devise a carline that will not only be capable of carrying a considerable vertical load but will be capable of offering considerable resistance to the stresses that tend to distort the car frame; and to devise a carline of great strength and light weight that may be produced with great economy.

The invention consists principally in a single-piece carline of pressed steel, wherein the end portions are widened out and provided with stiffening corrugations that extend longitudinally from the ends thereof; it also consists in a carline that is provided with a medial hollow rib or inverted channel extending the full length thereof and tapering from the middle to the respective ends in conjunction with longitudinally extending ribs in the four corner portions of said carline; it also consists in the arrangements and combinations of parts hereinafter described and claimed.

In the accompanying drawing, wherein like numerals refer to like numbers wherever they occur,

Fig. 1 is a plan view of a carline embodying my invention shown in connection with the side plates of a car;

Fig. 2 is a side elevation of the carline, the side plates being shown in section and the purlines being indicated by dot and dash lines;

Figs. 3 and 4 are cross-sections through the carline on the planes indicated by the dotted lines 3—3 and 4—4, respectively, in Fig. 1; and

Fig. 5 is a plan view illustrating a modified form of carline.

The carlines A and B shown in Figs. 1 and 5 of the accompanying drawings are each pressed up from a rectangular blank of sheet metal. The middle portion of the

blank from which each carline is formed is pressed up into the form of a hollow rib or inverted channel 1 that extends from end to end of the carline, leaving the side marginal portions of the blank projecting laterally from the bottom of said hollow rib in the form of flanges 2. Each carline is pitched from the end to the middle, and the hollow rib thereof is pitched at a higher inclination than the lateral flanges; that is, the vertical members of the hollow rib are deeper at the ridge than at the ends of the carline, so that the hollow rib tapers from ridge to ends. The width of the hollow rib of the carline A is widest at the ridge and gradually diminishes towards the ends, so that said hollow rib tapers from ridge to ends in width as well as in depth. The hollow rib of the carline B is of uniform width from ridge to points intermediate the ridge and ends and gradually diminishes from said points towards the ends.

In consequence of the tapering of the hollow ribs of the carlines A and B the lateral or base flanges of the carline A increase in width from ridge to ends and the base flanges of the carline B increase in width from points midway of the ridge and ends to said ends, thus providing wide bearings on the side plates C of the car. In order to increase the strength of the corner portions of the carline in resisting the stresses to which it will be submitted under service conditions, a longitudinal hollow rib 3 is pressed up in each corner portion. Each of these corner ribs extends from the end of the carline at least one-fourth of the way to the ridge and thence preferably in a gradual curve to the edge of the carline. The ends of the carline are provided with bolt-holes spaced widely apart in position for use in securing the carline to the side plates of the car.

The carline above described has numerous advantages. In the first place, it is not only made of a single sheet of metal but is well adapted to be pressed in a single operation and without injury to the metal. In the next place, it is designed not only so that a light weight of metal will carry a considerable portion of the vertical load of the roof, but it is especially well adapted to offer resistance to the torsional stresses that

tend to rack and weave the car body and to the horizontal stresses that tend to throw the car body out of square. At the same time, the wide spread of the holes for the 5 rivets 4 by which it is secured to the side plates of the car cooperates in accomplishing said functions, especially in accomplishing the function of a brace or gusset in stiffening the roof frame against horizontal 10 forces tending to distort said frame. It may be noted that, in case the stresses become so excessive as to overcome the resistance of the carline, the carline is adapted to yield thereto by bending to a limited extent without fracturing and with full capacity for restoring itself to its original condition without permanent injury.

What I claim is:

1. A sheet metal carline whose middle 20 portion is made in the form of a hollow rib that tapers in width and in depth from ridge to ends and whose lateral base portions widen from ridge to ends, each lateral portion comprising a hollow rib that 25 extends inwardly from the end thereof.

2. A sheet metal carline pressed from a rectangular blank whose middle portion is made in the form of a hollow rib open at the bottom and whose lateral bottom portions widen from ridge to ends and form 30 wide bearings for the side plates, each lateral portion having a hollow rib open at the bottom that extends inwardly from the end thereof at least one-fourth of the distance to the ridge.

3. A pressed metal carline whose longitudinal middle portion is made in the form of a hollow rib and whose lateral portions are wider at the ends than at the ridge, said

hollow rib being wider at the ridge than at 40 the eaves.

4. A sheet metal carline whose middle portion is made in the form of a hollow rib that is of greater depth and width at the ridge than at the ends and whose lateral 45 portions are wider at the ends than at the ridge.

5. A sheet metal carline whose middle portion is made in the form of a hollow rib that is of greater depth and width at the ridge than at the ends and whose lateral 50 portions are wider at the ends than at the ridge, each lateral portion comprising a hollow rib that extends inwardly from the end thereof.

6. A single piece metal carline pressed from a rectangular sheet comprising a hollow rib open at the bottom and having lateral base flanges throughout the length of the carline, said base flanges having hollow ribs open at the bottom extending from the ends thereof at least one-fourth of the distance to the ridge and thence to the outer 60 edges of the respective flanges.

7. A single piece sheet metal carline comprising a hollow rib open at the bottom and extending the whole length thereof without any interruptions of the continuity of its surfaces and having laterally extended flanges at the bottom thereof throughout its 70 length, and longitudinally extending corrugations in the corner portions of said flanges extending inwardly from the ends of said flanges and opening downwardly.

Signed at Parnassus, Pa., this 17th day 75 of February, 1922.

CHARLES DAVID BONSALL.
